UNITED STATES PATENT OFFICE.

SIDNEY E. KELSEY, OF KANSAS CITY, MISSOURI.

APPARATUS FOR DISTILLING HYDROCARBON OR OTHER LIQUIDS.

1,302,669.

Specification of Letters Patent.

Patented May 6, 1919.

Application filed September 20, 1916. Serial No. 121,316.

To all whom it may concern:

Be it known that I, SIDNEY E. KELSEY, a citizen of the United States, residing at Kansas City, in the county of Jackson and 5 State of Missouri, have invented certain new and useful Improvements in Apparatus for Distilling Hydrocarbon or other Liquids; and I do declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

My invention relates to apparatus for distilling hydro-carbon or other liquids and has for its principal object to effect molecular change in compounds, such as are contained in petroleum and products resulting 20 from the distillation of coal.

It is also an object of the invention to provide for automatic variation of the flow space of the vapor passing from the still to 25 a condenser, by conducting the vapors over a body of suitable fluid, whereby the cross sectional area of the flow space may be varied by ejection of the regulating fluid in accordance with the pressure of the vapor, 30 thereby relieving the still and the channels through which the vapor is conducted.

It is also an object of the invention to provide for by-passing the vapors directly from the still to the condenser under certain 35 conditions.

In carrying out the invention I have provided improved details of structure, the preferred forms of which are illustrated in the accompanying drawings, wherein:—

40 Figure I is a perspective view of an apparatus embodying my invention and adapted for distilling liquid in accordance therewith.

45 Fig. II is a horizontal section of the combined regulating and superheating vessel on the line II—II, Fig. III.

50 Fig. III is a vertical section on the line III—III, Fig. II, showing the regulating fluid partly expelled from the vapor channel.

55 Fig. IV is a perspective view of one corner of the combined regulating and superheating chamber, parts being broken away for better illustration.

Fig. V is a longitudinal section of end 55 portions of the still.

Fig. VI is an enlarged longitudinal section of the vapor and liquid filter.

Fig. VII is a sectional view of parts of one of the conduits, particularly illustrating 60 the flexible expansion joint.

Referring more in detail to the drawings:—

1 designates a furnace, comprising the 65 separate still and superheating chambers 2—3, the still chamber being lined with refractory material (not shown), and the superheater chamber being open at the top and provided with a ledge 5, for supporting a vessel presently described, the still and 70 superheater chambers being separated by a bridge wall 6, having a passage way 6' therein through which products of combustion may pass, so that when there is fire under the superheater the products of combustion may exhaust into the still chamber 75 and heat the still.

Located in the still chamber 2 is a still 7 of any suitable construction, and leading 80 from the top of the still, preferably adjacent to one end thereof is a feed pipe 8, having a three way fitting 9 thereon. Opening to one connection of the fitting 9 is a pipe 10 that connects in one end of a filter case 11 containing mineral wool, or the like 12, 85 and opening from the upper side of said casing, is a pipe 13 that leads from the bottom of a liquid supply tank 14; the pipe 13 containing a valve 15 whereby supply of 90 liquid from the tank to the still may be controlled. The pipe 10 and filter 11 are inclined and leading from the end of the filter opposite the pipe 10 is a pipe 16 that is also inclined and leads to a condenser 17, which 95 will presently be more fully described. The filter is provided with a drain pipe 18 having a valve 18', through which accumulations in the filter may be exhausted.

The pipe 8 leads to near the bottom of the still 7, so that the liquid to be vaporized 100 may be delivered below the liquid level of the still and form a seal at the lower end of pipe 8, and leading from near the top of the still, adjacent the end opposite the intake of pipe 8, is a vapor pipe 19 containing 105 an expansion joint 20 wherein expansion or contraction of the vapor pipe may take place without damage to the pipe; the said

pipe 19 leading to the front of the furnace and extending downwardly therealong to a well 21, wherein condensation from the vapors may be collected.

- 5 Located within the forward furnace chamber 3 is a vessel 23 having tapering sides and provided at its upper edges with a flange 24, whereby the vessel may be supported on the chamber ledge 5, so that 10 the vessel may be easily inserted in or removed from the chamber, the bottom of the vessel being preferably corrugated for a purpose persently mentioned and having at its forward corners the risers 26-27, 15 provided with the intake and delivery ports 28-29 respectively. Seated on the bottom of the vessel 23 is a duct or channel 30 preferably coiled as shown in the drawing and wherein each individual member is of inverted U-shaped cross section, forming a 20 duct or channel open at the bottom and closed at the sides and top, the end of the duct or channel comprising heads 32-33 that overlie the risers 26 and 27, so that 25 vapor may be delivered through one of the risers into the duct or channel head and be delivered from the opposite head into the opposite riser. Inclosing the duct or channel is a cover member 35, the side and end 30 members of which seat on the bottom of the vessel 23 and the top of which is provided with a vent stack 36 that extends upwardly through a pad of insulating material 37 that lies on the cover 35 and serves to retain heat 35 within the chamber.

The vessel 23, the channel or duct 30 and the cover 35 are all of suitable refractory material, and located within said vessel is a mass 38 of less refractory material such as 40 lead, zinc, glass or the like, which when melted immerses the lower portions of the duct or channel and the sides and ends of the cover 35, and forms a sealed vapor passageway 39 in the upper portion of the duct 45 or channel, the normal level of said mass being below the ports 28-29 of the risers 26 and 27 in order to obviate loss of the material into the risers. The vapor pipe 19 leading from the still to the well 21 has a branch 50 41 connecting with the riser 26 so that vapors delivered from the still may flow through the riser into the intake end of the duct or channel 30 and leading from the opposite riser 27 is the branch 42 of a pipe 43, the 55 lower end of which delivers to a well 44 while the body of the pipe leads upwardly to a point above the level of the still and thence is inclined downwardly to a connection with the fitting 9, so that vapors delivered from the outlet end of the duct or 60 channel pass up through the pipe 43 and thence downwardly to the fitting, it being apparent that any condensation in the pipe will flow either to the well 44 or into the fitting 9, the latter draining back into still

through the pipe 8. The pipe 43 also contains a flexible expansion joint 45, and the pipe 19 and pipe 43 contain valves 46-47, whereby flow of vapor therethrough may be controlled.

70 Leading through the front wall of the furnace from the header 48 are pipes 49, through which fuel may be delivered for burning in the superheating chamber 3.

The condenser 17 which I illustrate in the 75 drawings, comprises the tank 17 and a contained coil 53, preferably of convolute form and having the gas outlet 54 and liquid outlet pipe 55 at the same end, the vapor pipe 16 leading into the center of the coil, so that 80 the vapors pass in a circuitous route through the coil in order to secure the cooling and condensing effects.

When the mass of heating material in the 85 superheater vessel is at the proper temperature, the flow line 19 is opened, so that vapors may pass from the still into the intake riser 26, and thence into the duct or channel 30, above the molten mass 38, it being apparent that any condensate of the 90 vapor passes down into the well 21, and only the vapor passes into the conduit. When the vapor reaches the duct or channel it flows therethrough in a circuitous path until it reaches the outlet end of the conduit 95 when it passes into the riser 29 through which it is conducted to the pipe 43 and thence into the pipe 10 through which it flows over the stream of oil passing to the still from the filter 11, and through the filter 100 into pipe 16 and thence to the condenser, it being apparent that any condensation in the pipe 43 will pass either to the well 44 or through the pipe 8 into the still. By passing the vapors and gasses through the mineral wool or the like in the filter 11, the 105 heavy vapors will condense therein and flow back to the still, while lighter vapors and gases will pass on up through pipe 16 to the condenser, the vapors passing over the down-flowing stream of supply fluid, so that the streams may flow in opposite directions without interfering. Should the vapors be supplied from the still to the superheater in 110 more than the normal volume, or should the expansion in the conduit become excessive, the pressure of the vapors will force the molten mass 38 downwardly in the duct or channel so that it will flow out beneath the 115 lower edges of the duct or channel into the spaces between the convolutions, thereby increasing the cross sectional area of the flow space for vapors in the duct or channel, so that it may accommodate the greater volume 120 of vapor and relieve the duct or channel, the still and the conduits from excessive pressure, it being apparent that the fluidity of the molten mass provides the automatic regulation of cross sectional area in the duct or 125 channel.

The relief valve 56 in the pipe 57 leading from the pipe 19 to the condenser pipe 16 may be set to open under a certain pressure, so that should the pressure in the still become excessive, the vapors may pass from the still direct to the condenser without passing through the superheater. Should, however, the pressure of vapor in the still, the conduit, and the superheater reach an extraordinary point, or should the relief valve fail to operate, the extraordinary pressure in the superheater will cause the vapors to force all the molten mass out of the duct or channel and themselves pass out beneath the edges of said duct or channel and up through the molten mass into the cover 35, from which they may escape into the atmosphere through the vent 36, thereby preventing damage to the apparatus by explosion or otherwise.

The pressure required in operating is just that which is necessary to cause the vapors to move with proper velocity through the coils and it is limited by the weight of a column of the heating material reaching from the bottom of the conduit to the upper surface of said heating material. I do not desire to be limited to any particular pressure but in actual practice a pressure between 4 and 16 ounces amply serves the purpose. The temperatures employed may vary with material operated upon and the quality of the product desired and may conveniently vary between 570° F. and 1150° F.

According to my invention I am enabled to provide for automatic pressure regulation or more properly speaking to maintain the pressure in the conduit substantially constant by means of the variation in the effective cross sectional area of the conduit for the reason that the amount of pressure in the still depends upon the amount of vapor above the liquid. As the capacity of the discharge pipe increases, the amount of vapor withdrawn increases and the rise of pressure is retarded thereby. Recognizing that the capacity of a pipe varies directly as its cross sectional area (friction neglected) it is obvious that a slight increase of pressure in the still and in the conduit causes a drop in the level of the heating material in the conduit and a consequent increase in the cross sectional area, thereby increasing the capacity of the conduit. This increased flow of the vapor from the still tends to diminish the accumulation of vapor in the still so that the automatic regulation at nearly constant pressure necessarily follows.

Having thus described my invention what I claim as new therein and desire to secure by Letters-Patent, is:—

1. In an apparatus for distilling hydro-carbon or like liquid, a vessel, an inverted duct or channel seated in said vessel open at its lower portion throughout its entire

length to the space in said vessel, a mass of sealing fluid contained within the vessel and immersing the lower portion of the duct or channel, a still, means for heating said still and said vessel, a condenser, conduits leading from the still to the duct or channel and from the duct or channel to said condenser, whereby variation in pressure of the vapors determines the level of the fluid in said vessel to provide for variations of the cross sectional area of the flow space for the vapor.

2. In an apparatus for distilling hydro-carbon or like liquid, a vessel, an inverted duct or channel seated in said vessel, open at its lower portion throughout its entire length to the space in said vessel, a mass of sealing fluid contained within the vessel and immersing the lower portion of the duct or channel, a still, means for heating said still and said vessel, a condenser and conduits leading from the still to the duct or channel and from the duct or channel to said condenser, whereby variation in pressure of the vapors in the duct determines the level of the fluid in said duct and in said vessel to provide for variation of the cross section of the flow space for the vapor, and a vent for such vessel whereby the vapors may escape upon completely expelling the sealing fluid from said duct or channel.

3. In apparatus for distilling hydro-carbon or other liquid, consisting of a suitable vessel, an inverted duct or channel seated in said vessel, a cover for said duct or channel, a mass of molten fluid in said vessel immersing the lower portion of the duct or channel and the lower portion of said cover, a still in communication with one end of the duct or channel above the level of said molten fluid, and a condenser in communication with the opposite end of the duct or channel, also above the level of said molten fluid.

4. In apparatus for distilling hydro-carbon or other liquid, consisting of a suitable vessel, an inverted duct or channel seated in said vessel, a cover for said duct or channel, a mass of molten fluid in said vessel immersing the lower portion of the duct or channel and the lower portion of said cover, a still in communication with one end of the duct or channel above the level of said molten fluid, and a condenser in communication with the opposite end of the duct or channel, also above the level of said molten fluid, and a vent for said cover.

5. In apparatus for distilling hydro-carbon or other liquid, consisting of a suitable vessel, an inverted duct or channel seated in said vessel, a cover for said duct or channel, a mass of molten fluid in said vessel immersing the lower portion of the duct or channel and the lower portion of said cover, a still in communication with one end of the duct or channel above the level of said molten

fluid, and a condenser in communication with the opposite end of the duct or channel, also above the level of said molten fluid, a vent for said cover, and an insulating cover for 5 said cover.

6. In apparatus for distilling hydro-carbon or other liquid, consisting of a super-heater, a still, a vapor conduit leading from the still to the super-heater, a conduit in the 10 super-heater and having a variable cross sectional area to provide for pressure regulation within the still, a condenser, a vapor conduit leading from the super-heater to the condenser, and a by-pass containing a relief 15 valve for by-passing vapors from the still to the condenser, whereby vapors may be conducted direct from the still to the condenser at a certain predetermined pressure.

7. In apparatus for distilling hydro-carbon or other liquid consisting of a super-heater, a still, a vapor conduit leading from the still to the super-heater, a continuous 20 serpentine conduit in the super-heater and communicating with the conduit from the still, said serpentine conduit being expansible to vary the effective cross sectional area 25 thereof, a condenser, a vapor conduit leading from the super-heater to the condenser and communicating with the serpentine conduit and a by-pass containing a relief valve 30 for by-passing vapors from the still to the condenser whereby vapors may be conducted direct from the still to the condenser.

8. In apparatus for distilling hydro-carbon or other liquid, a still, a super-heater, a 35 sealing fluid in the super-heater, a conduit open at its lower portion throughout its entire length and partially immersed in the sealing fluid, means for effecting communication between the still and the conduit, a 40 condenser, means for effecting communication between the condenser and said conduit,

the effective cross sectional area of said conduit being variable by the rise and fall of the sealing fluid due to variations of pressure 45 generated in the still.

9. In apparatus for distilling hydro-carbon or other liquid, a still, a super-heater, a sealing fluid in the super-heater, a conduit open at its lower portion throughout its entire length and partially immersed in the sealing fluid, means for effecting communication 50 between the still and the conduit, a condenser, means for effecting communication between the condenser and said conduit, the 55 effective cross sectional area of said conduit being variable by the rise and fall of the sealing fluid and to variations of pressure generated in the still and a cover inclosing the conduit, said cover being open at its 60 lower portion and having its side walls partially immersed in the sealing fluid.

10. In apparatus for distilling hydro-carbon or other liquids, a still, a super-heater, a conduit in said super-heater comprising an 65 elongated tube open at its bottom, a sealing fluid in said super-heater in which the side walls of the conduit are embedded and means for exhausting vapor from the elongated conduit, the effective cross sectional area of said 70 conduit being variable due to the rise and fall of the sealing fluid whereby a continuous pressure regulation in the conduit is affected.

11. A super-heater for use in distilling 75 hydro-carbon or other liquids, comprising a vessel having an inlet and an outlet, a removable inverted elongated duct or channel contained in said vessel and open at its lower portion throughout its entire length to the 80 space in said vessel and a sealing fluid in said vessel immersing the lower portion of the duct or channel.

SIDNEY E. KELSEY.
